UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

DUMPING-CAGE FOR CRUSHERS AND PULVERIZERS.

No. 836,162.

Specification of Letters Patent.

Patented Nov. 20, 1906.

Application filed July 24, 1905. Serial No. 271,019.

To all whom it may concern:

Be it known that I, MILTON F. WILLIAMS, a citizen of the United States, residing at St. Louis, Missouri, have invented a certain new and useful Improvement in Dumping-Cages for Crushers and Pulverizers, of which the following is a full, clear, and exact description, such as will enable others skilled in the art to which it appertains to make and use the same, reference being had to the accompanying drawings, forming part of this specification, in which—

Figure 1 is a longitudinal sectional view through my improved machine. Fig. 2 is a horizontal sectional view on the line 2 2 of Fig. 1. Fig. 3 is a longitudinal sectional view of a modified form of cage-dumping mechanism, and Fig. 4 is a longitudinal sectional view on the line 4 4 of Fig. 3.

This invention relates to a new and useful improvement in dumping-cages for crushers and pulverizers, the object being to construct a cage in such manner that when the machine chokes it is possible to dump the contents thereof without raising the cover and removing the material from the top.

In the operation of my machine, especially where electric motors are employed as a driving medium, it sometimes happens that the fuse will blow out or other accidents happen during the time that the machine is in operation, causing the machine to stop and leaving the material being operated upon in the machine. Under these circumstances it is impossible to start the machine without first removing such material, it being necessary to get the machine up to full speed before introducing the material thereinto to be reduced.

My present invention therefore consists in making the grinding-surface or cage, with which the revolving beaters coöperate to reduce the material, wholly or partly movable, means for moving the same extending to the exterior of the machine, whereby in the event that the machine stops with a load or becomes choked it is possible for the operator to dump the contents of the cage and free the machine.

In the drawings, 1 indicates the side plates of the casing, and 2 is the cover.

3 indicates the breaker-plate, arranged at the front end of the machine and on which

the material is first operated upon by the revolving hammers or beaters 4, which are pivotally mounted in the hammer-supports 5, arranged on a transversely-disposed shaft 6.

7 indicates the cage or grinding-surface, which in this instance is made of two hinged parts, the free edges of which are contiguous. 60 Connected to the opposite sides of the free edges of the cage-sections in the form shown in Figs. 1 and 2, by means of pins 17, are toggle-links 8, whose companions 18 are pivotally connected by pins 19 to the side plates 65 1 of the machine. A yoke-shape operating-link 9 is fastened to the junction of these pairs of toggles by a pin 21, and said link 9 is connected by a pin 23 to a rack-bar 10, with which meshes a pinion 11, on whose shaft is 70 a hand-wheel 12, located outside the casing.

By this construction when it is desired to dump either of the sections of the cage it is only necessary to operate the hand-wheel 12, so as to move its operating rack-bar 10 outwardly for actuating the link 9 to "break" 75 the toggle, so as to permit the connected cage-sections to drop, as shown by dotted lines in Fig. 1.

When the cage is in normal position, as shown in full lines in Fig. 1, the toggle-links form an efficient and rigid support therefor by reason of their pivotal centers being in a line.

In Figs. 3 and 4 the cage-sections 7^a are so 85 mounted that their free ends are adjacent; but instead of connecting the toggle mechanism to the free ends of said cage-sections I arrange pivoted levers 25 with rollers 26 on their upper ends riding under the curved side 90 bars of the cage-sections. These levers 25 are pivoted at 27 to the side plates of the machine and have connected to them by pins 29 a yoke 9^a, which in turn is connected to a rack-bar 10^a, whose rack meshes with a pinion 11^a, on whose shaft is arranged a hand-wheel 12^a. The operation of this construction is obvious.

Having thus described the invention, what is claimed as new, and desired to be secured by Letters Patent, is—

1. In a crusher or pulverizer, the combination of a sectional grinding-surface, the sections of which are independently pivoted, and an independent means connected to 105 each section and extending to the outside of

the machine for actuating the said sections to separate their free edges to dump the material in the machine; substantially as described.

5 2. In a machine of the character described, the combination of a casing, revolving hammers or beaters, a sectional grinding-surface, the sections of which are pivoted at different points so that the free edges of said sections 10 are adjacent each other, and independently-operable means connected to said sections and extending to the outside of the casing whereby the free edges of said sections may be separated to dump the material in the 15 machine; substantially as described.

3. In a crusher or pulverizer, the combination of a casing, revolving hammers or beaters, a grinding-surface composed of independent sections mounted on fixed pivots, 20 the free edges of said sections being adjacent each other, independently-operable mechanism arranged beneath the free edges of said sections for actuating said sections to sepa-

rate their free edges, said mechanism including a rack-bar, a pinion in mesh with said rack-bar, and a hand-wheel conjoined to said pinion, said hand-wheel being located on the outside of the casing; substantially as described.

4. In a crusher or pulverizer, the combination of a casing, revolving hammers or beaters, a grinding-surface comprising a plurality of movable sections, a toggle mechanism connected to said sections, and means extending outside of the machine and connected to said toggle mechanism for operating the same and its connected sections to dump the material in the machine; substantially as described.

In testimony whereof I hereunto affix my 40 signature, in the presence of two witnesses, this 14th day of July, 1905.

MILTON F. WILLIAMS.
